UNITED STATES PATENT OFFICE.

JOHN YOUNG, OF NEWARK, NEW JERSEY.

TURBINE STEAM-ENGINE.

SPECIFICATION forming part of Letters Patent No. 645,283, dated March 13, 1900.

Application filed April 13, 1898. Serial No. 677,428. (No model.)

To all whom it may concern:

Be it known that I, JOHN YOUNG, engineer, a citizen of the United States, residing at Newark, in the county of Essex, in the State 5 of New Jersey, have invented a certain new and useful Improvement in Rotary Impact or Turbine Steam-Engines, of which the following is a specification.

My improved engine is of the class in which 10 the steam admitted at one point is allowed to move to another point by being alternately deflected first in one direction by stationary guides and then in another direction by a series of guides or wings carried on a part 15 which is free to move. It is the principle involved in water-wheels of the class known as "turbine," and the term "turbine" applies with some propriety to this class of steam-engines, the motion being much more lively with steam 20 than with water, so as to tend to induce an extremely-rapid motion of the wheel, but becoming less in force, due to the levity of the fluid.

I have devised an improvement involving a simple and efficient construction whereby 25 the manufacture is facilitated, and smooth holes may be bored by ordinary tools in what would otherwise be almost impracticable positions and directions.

The accompanying drawings form a part of 30 this specification and represent what I consider the best means of carrying out the invention.

Figure 1 is a central section at right angles to the axis. Fig. 2 is a section on the line 2 35 2 in Fig. 1. Fig. 3 is a section of a portion showing a modification adapted to receive the steam at the periphery and to discharge at the center. Fig. 4 is a cross-section of a portion, showing a further modification.

Similar letters of reference indicate like 40 parts in the several figures where they appear.

A is a stout casing of cast-iron or other suitable material, supernumerals, as A', being used to designate special parts thereof when 45 necessary. The casing is made in two parts, which may be exactly similar, applying on opposite sides of the wheel. A description of one will serve for both.

B is a shaft to which is firmly attached a hub 50 B', carrying a narrower ring B² on its mid-length. To this is firmly united a wider ring

B³, upon which is a narrow ring B⁴, another wide ring B⁵, another narrow ring B⁶, and so on. I have shown the series terminating with the narrow ring B⁸, but the series can be carried out further, if desired, in any case, taking care to have the casing which incloses them made to correspond. The ring B³ is bored with twenty-eight holes b, the ring B⁵ with thirty-four holes somewhat larger, and 55 the ring B⁷ with forty holes larger still. All the holes are inclined, so that the steam will drive the wheel forward as it moves outward through these holes.

The two parts of the casing A are formed 60 in part of separate rings tightly set and partly embedded in the inner faces, which are presented toward the rapidly-revolving wheel. The rings make the faces match exactly to the sides of the wheel which are presented thereto. 70 The innermost ring is marked A² and matches against the narrow portion B² of the wheel. The next ring A⁴ matches against the narrow ring B⁴ of the wheel. The next ring A⁶ matches against the narrow ring B⁶ of the wheel. 75 Lastly, the outermost ring A⁸ matches against the outermost narrow ring B⁸ of the wheel. All are adapted to make a tight and easy fit of the casing against the adjacent surfaces of the wheel, matching not only against the narrow portions B², B⁴, B⁶, and B⁸, but also against the wide portions B³, B⁵, and B⁷. All the fixed rings A² A⁴ A⁶ A⁸ are bored with holes 80 a, which are inclined in the opposite direction to the holes b. The steam in moving 85 through these holes a is always thrown in the direction to impel the wheel forward. The holes a increase in number and size in the several successive rings. The rings A² have each twenty-one holes, the rings A⁴ have each 90 thirty-one holes of larger diameter, the rings A⁶ have each thirty-seven holes of still larger diameter, and the rings A⁸ have each forty-three holes still larger.

The shaft B, with its hub B' and rings B², 95 &c., is allowed to revolve rapidly.

The innermost rings A² are each formed integrally with the main body of the casting A, on which it is set. The other rings A⁴, A⁶, and A⁸ are formed separately and are fitted 100 by tightly driving into corresponding close-fitting annular recesses in the parts A. When

in position, they are adapted to serve with the other portion A, in which they are set, as a single rigid unit.

Steam admitted from a boiler (not shown) 5 through the pipes A⁹ and vertical passages A¹⁰ to the central space surrounding the hub of the wheel flows outward through the several holes a in the rings A², A⁴, A⁶, and A⁸, being each time deflected to impel the wheel 10 forward. Between the rings A² and A⁴ it strikes the rings B³ and moves through the holes b therein, inclined in the opposite direction. So with regard to its passage through the other several rings, at each passage lowering its pressure and becoming increased in bulk, requiring more numerous and larger holes for its passage. The steam acts on the wheel at each stage, both by percussion and reaction, the percussion due to its deflection 15 in passing through the apertures a in the fixed rings and the reaction due to the different deflection in the other direction, rearward relatively to the motion of the wheel, by its passage through the apertures b in the revolving parts. It is discharged at the rim into an annular passage a', from whence it is allowed to escape through a liberal passage a² and may 20 be led by a pipe A¹¹ to any point desired. If the conditions are favorable, it may be discharged 25 into a vacuum, so that the engine may be a condensing one.

Power is communicated from the shaft B through a gear-wheel B⁹, which engages with a train of reducing-gearing (not shown) by 30 which the speed is reduced, and the power may be made efficient in the ordinary and long-approved manner.

It is important to balance the wheel B very 35 perfectly. The manufacture of the rings each separately from a sound casting or forge, with the holes cleanly bored, tends to make a very nearly perfect balance without attention. Any balancing which the wheel is found to require when completed may be attained by 40 the removal of small quantities at the proper point on the outer edge or rim.

I attach importance to the construction of the wheel and also of the inner faces of the two parts of the casing A with separately-formed rings, because it makes it easier to 45 drill the holes while the rings are separate and subsequently to bring them into their proper relation to the other parts by combining such separately-formed rings rigidly together, the 50 proper rings being combined to form the wheel and the proper rings having the holes oppositely inclined to form the proper directing and abutment parts of the casing.

Modifications may be made without departing 55 from the principle or sacrificing the advantages of the invention. The number and sizes of the holes in the several rings may be varied. Their angular positions may also be somewhat varied. There may be more or less difference between the aggregate area in the inner rings and the outer rings as compared with those in the intermediate. Other means

may be employed for holding the fixed rings A⁴ A⁶ A⁸, among which may be screws inserted from the outside. Screws may bind together 70 the rings B² B³, &c. One such is shown in Fig. 3.

It is not essential to the success of the invention that the steam shall be introduced at the center and discharged at the periphery, 75 as shown. By making the proper changes in the diameters of the holes for the passage of the steam, so that there shall be a greater aggregate area of apertures through the innermost rings and a lesser aggregate area of the 80 holes in the outermost rings, I can introduce the steam at the periphery and discharge it at the center. Such an arrangement will allow a reduction in the strength and thickness of the parts A by bringing the intensely-high-pressure portion to the periphery adjacent to the holding-bolts and leaving the middle exposed only to the distending strain due to the much-reduced terminal pressure. Fig. 3 shows such an arrangement. I prefer the arrangement first described.

Instead of making the wide rings and the narrow ones each separate one wide ring and one narrow ring can be made together.

In adapting my engine to receive the steam 95 at the periphery and discharge at the center I can make the wide rings wider in the center than at the periphery and get room for a larger number of the holes in the innermost. Fig. 4 shows these features. This construction, equally with that before described, allows the inclined holes to be drilled with perfection and ease by ordinary tools.

I claim as my invention—

1. In a rotary engine of the character described, a motor-wheel comprising alternate narrow and wide independent ring-sections fitted together to serve as a unit and presenting on opposite faces a series of concentric ribs, the latter having oblique perforations, substantially as herein specified.

2. In a rotary impact steam-engine of the character described, the construction of the revoluble wheel in rings having oblique perforations and formed separately and fitted rigidly together to serve as a unit, in combination with a fixed inclosing casing the inner faces of which are provided with rings formed separately from each other and from the body portions of the casing, having perforations inclined oppositely to those of the wheel-rings and adapted to serve therewith when subjected to strong currents of steam, substantially as herein specified.

3. In a rotary impact steam-engine, a wheel 125 having concentric rings formed in independent sections and projecting on both faces and perforated obliquely, in combination with a casing having closely-fitted rings formed independently of each other and of the supporting portions and with perforations oppositely inclined, provided with the steam-passages A¹⁰, A¹⁰, extending radially of the casing on each side, the two pipes A⁹, A⁹, con-

5 nected thereto, the annular steam-passage a' at the periphery, the passage a^2 and the single pipe A^1 , connected thereto, all arranged for joint operation substantially as herein specified.

4. In a rotary engine of the character described, a wheel having concentric rings projecting on both faces and perforated obliquely as indicated by a , the rings being separately 10 formed and fitted together to serve as a unit, in combination with a closely-fitted casing in two parts having rings to match and provided

with apertures b , inclined in the opposite direction relatively to the radius, the rings of each casing part being also separately formed and fitted to serve as a unit, substantially as herein specified. 15

In testimony that I claim the invention above set forth I affix my signature in presence of two witnesses.

JOHN YOUNG.
